DESIGN.

E. FORREST.

PHONOGRAPH CASE OR CABINET.

APPLICATION FILED JAN. 31, 1918.

52,214.

Patented July 23, 1918.

Edwin Forrest, Inventor

By his Attorney
Thayor & Hill

UNITED STATES PATENT OFFICE.

EDWIN FORREST, OF NEW YORK, N. Y.

DESIGN FOR A PHONOGRAPH CASE OR CABINET.

52,214.

Specification for Design. Patented July 23, 1918.

Application filed January 31, 1918. Serial No. 214,782. Term of patent 7 years.

To all whom it may concern:

Be it known that I, EDWIN FORREST, a citizen of the United States, residing at New York city, in the county of New York and State of New York, have invented a new, original and ornamental Design for Phonograph Cases or Cabinets, of which the following is a specification, reference being had to the accompanying drawing, forming part thereof.

The figure is a front elevation of a phonograph case or cabinet illustrating my design.

I claim:

The ornamental design for a phonograph case or cabinet, as shown.

EDWIN FORREST.
